DRILL BIT

Martin Hokanson, Duluth, Minn., assignor to
Eidco, Inc., Duluth, Minn., a corporation of
Minnesota

Application October 26, 1936, Serial No. 107,563

10 Claims. (Cl. 255—64)

This invention relates to improvements in drill bits and pertains to that class of bit illustrated in my copending application Ser. No. 26,418.

The principal object of the present invention is 5 that of providing a more efficient, faster cutting, and durable bit of this type.

Another object is to provide such a bit having a cutting face in which a leading portion thereof will effectually perform the work necessary 10 with the least wear to that portion and assist materially in lessening the work necessary of accomplishment by the following portion.

Another object is to provide such a bit with 15 novel and more efficient fluid discharge therefore. Still other objects and advantages of the invention will appear in the following description thereof.

Referring now to the accompanying drawing, forming part of this application, and wherein like 20 reference characters indicate like parts:

Figure 1 is a side elevation of one of the improved bits.

Figure 2 is a similar view taken at right angles to Figure 1.

Figure 3 is a plan view of the cutting face of the bit showing its relation to a hole formed thereby.

Figure 4 is a section on the line 4—4, Figure 3.

In the drawing, 1 represents the body portion 30 of the bit, the shank end thereof being hollow and internally screwthreaded as at 2 for the reception of any suitable extension necessary for such attachment. In this illustration of the embodiment 35 of the invention I have shown the sides of the bit on one diameter as diverging, while upon the opposite diameter they converge, that is to say, the periphery of the cutting face of the bit is of substantially elliptical form.

In the face of the bit are formed two concavities of cone shape, the apexes of which are illustrated at 3 and these concavities are so shaped and of such an extent as to cause their extreme circumferential edges to meet, or become tangent at the axis of the bit, as indicated at 4. As it is desired in this instance to make the central cutting portion of the face of the bit the leading portion, or that which operates upon a smaller diameter of the hole being drilled; the outermost slightly major portion of the edges of the concavities are cut away as at 5 and on a plane parallel 50 with and spaced from that of the leading portion of the face of the bit along the axis thereof, thus forming a face stepped upon opposite sides as clearly illustrated in Figures 1 and 4 of the drawing. Thus it is apparent that the inner walls of 55 the cutting edges 6—6, which in this instance

are shown as tangent at the axis of the bit, and the walls of the cutting edges 7—7, are formed by the two spaced cones above referred to, the apexes of which are indicated at 3. While these cutting edges on either side of the axis of the bit are in different planes and formed by the same cones, yet they are of approximately the same extent, that is their circumferential measurement is approximately the same, but readily possible of a ratio change by modification of the 10 cut away section 5 of the central portion; the length of the cutting edges 7 in the instant illustration being slightly greater than the length of the cutting edges 6. The outer inclined surfaces 8 of the stepped cutting edges 7, as well as the 15 outer inclined surfaces 9 of the inner cutting edges 6, are preferably of the same inclination as the innermost surfaces, though, obviously, and as various kinds of work might require, these inclinations may be varied. It is to be noted that 20 as a preferred ratio of inner and outer cutting edges, the termini of the former are defined by a circle intersecting or coincident with the axis of the cones which form the inner walls of same, resulting in the edges of the walls 10 of the ends 25 of the centermost portion of the bit being arcuate in plan view (see Fig. 3) with the outer surfaces thereof being parallel with the axis of the bit, though, obviously, such walls may be inclined, if preferred, as well as the inclination of both the 30 inner and outer walls of the cutting edges to vary the reinforcement of same, as desired.

As previously stated, a novel feature of the invention is the arrangement of water discharge orifices and this is accomplished by there being 35 formed in the bottom of the bore of the bit 2 an axial well 11 into which the bore of the bit rod, not shown, discharges, and the supply of water through the axis of the bit being too common in the art to require further illustration. From this 40 well axially is led a reduced bore 12 to the tangential point of the cutting edges 6, previously described, and where said reduced bore may be countersunk as desired for proper distribution of the water discharge therethrough. From opposite sides of the well 11 are inclined holes 13 leading to the concavities of the cutting edges and are novel in that they discharge within their respective concavities to one side of the apexes thereof, or in other words forwardly of said 50 apexes in respect to the travel of the bit. For example, in the illustration here shown and as viewed from the face of the bit (see Fig. 3), the travel of same during work is counterclockwise, so that the spalls from the bit are discharging rearwardly 55

- as quickly as possible and with the least effort on the part of the liquid being used; where, of course, if the bit traveled in the opposite direction the discharge of the holes 13 would be on the 5 opposite side of the apex of the cones from that illustrated. Thus formed, the discharge from the holes is readily led closer to the cutting edge of the bit and that without interfering with the strength of same, or the sharpening thereof.
- 10 From the above it is apparent that when this type of bit is used in connection with pneumatic jack hammers, drifting machines, stopers or the like, either as a part of the drill rod proper or a detachable bit, and in which cases the diameter 15 of the hole drilled rarely exceeds 2½", the areas of the two spaced faces may be, for average drilling, substantially equal.

It will also be understood that this type of bit is adapted for use in large hole drilling, such as 20 percussion drilling in connection with oil wells, quarries, and the like.

In practice it has been found that the reaming function of this type of bit is very effective as compared with that of the cross-bit, and that the 25 loss in gauge of the bit is comparatively little, which, of course, is of extreme importance, because it will result in a greater diameter of hole at the conclusion of the drilling operation than that accomplished by the cross bit. The reason 30 for this is the greater amount of wearing surface on the outside of the bit as compared with that of the cross-bit. Another advantage of this type of bit is that it does not rifle the hole like the common cross-bit, but leaves a smooth round 35 wall which also prevents excessive circumferential wear of the bit.

The resharpening of this bit is also very easily performed. The dulled cutting edges of the bit are sharpened from the outside with the same 40 angle as the original bit until it meets the circle of the cone. If a V-shaped grinding wheel is used for this, the same wheel can sharpen the cutting edges of the central cutting edges of the bit very nicely. If the cylinder of the central part 45 of the cutting edges needs to be reconditioned, it can be done at the same time as the taper of the bit is reconditioned.

Having thus described my invention, what I claim and desire to secure by Letters Patent, is: 50

1. A drill bit of the class described, characterized by the cutting face of said bit being stepped, forming two separate parallel portions of said face, the inner inclined surface of the cutting edges of said face upon either side of the 55 axis of the bit being formed by the outer surface of a cone common to the cutting edges in both planes.

2. A drill bit of the class described characterized by the cutting face of said bit being stepped, forming two separate parallel portions of said face, the inner inclined surface of the cutting edges of said face upon either side of the 60 axis of the bit being formed by the outer surface

of a cone common to the cutting edges in both planes, and the outer inclined surface of said cutting edges being formed as by the inner surface of a cone concentric with said cone defining the inner inclined surface. 5

3. A drill bit of the character described, characterized by the cutting face of said bit being formed upon two parallel planes spaced apart longitudinally the axis of the bit, and conical depressions in said face, the edges of which form 10 the cutting edges of the bit in both planes.

4. A drill bit of the character described, characterized by the cutting face of said bit being formed upon two parallel planes spaced apart longitudinally the axis of the bit, and conical 15 depressions in said face, the edges of which form the cutting edges of the bit in both planes, that portion of said face adjacent the axis of the bit being the leading portion during the cutting action of the bit. 20

5. In a drill bit of the character described including a shank, a cutting face comprising two central arcuately shaped cutting edges diverging outwardly in opposite directions from the center of the bit, and two opposed arcuate cutting edges, 25 one adjacent each of said central arcuate edges and of the same internal inclination as that of said arcuate cutting edges, each pair of said cutting edges being in a different plane.

6. The combination with a drill bit having a 30 concave cutting face and an axial bore therein, of a discharge opening from said bore into the concavity of the face and located upon the following side of said concavity in respect to its rotation while drilling. 35

7. A hollow drill bit characterized by having a pair of arcuate cutting edges meeting back to back adjacent the axial bore of said bit, and a substantially semi-circular cutting edge concentric with each of said arcuate edges, each pair of said 40 edges being in a different plane.

8. A drill bit of the character described, characterized by the cutting edges of the bit being formed by conical depressions in said bit and upon two parallel planes spaced apart longitudinally of and at right angles to the axis of the 45 bit.

9. A unitary drill bit of the character described, characterized by the cutting edges of the bit being formed upon separate parallel planes 50 spaced apart longitudinally of the axis of the bit, said cutting edges being formed by conical depressions extending in each plane.

10. A drill bit of the character described, characterized by the cutting edges of the bit being 55 formed by conical depressions in said bit, an axial water bore through said bit, and a discharge opening from said bore into each conical depression and located upon the following side thereof in respect to the rotation of the bit while in the 60 act of drilling.

MARTIN HOKANSON.
